Design for Animal Trap,

Patented June 6, 1865.

Blundenbille Game 1865

DES. 2081

Hubert L. Hart, of Unionville, Conn.

Letters Patented No. 9087-Dated June 6-1865.

Design for an animal trap.

The schedule referred to in these Letters Patent and making part of the same.

To all whom it may concern:

Be it known that I, Hubert L. Hart, of Unionville, County of Hartford and State of Connecticut, have invented or produced a new and original design for an animal trap; and I do hereby declare that the following is a full and exact description of the same, referring to the photographic views in which the same letters indicate like parts in each of the figures.

In the accompanying photographic views are shown a new and original design for an animal trap. A is the frame. B is the paw. C, the spring. D, the jaws. E, the set bar, all arranged and combined to produce a plain design for an animal trap.

What I claim, therefore, and desire to secure by Letters Patent is the design for an animal trap as herein illustrated and set forth.
